(57) CLAIM

The ornamental design for a shoe, as shown and described.

DESCRIPTION

FIG. 1 is a front perspective view of a shoe showing my new design;

FIG. 2 is a side view thereof;

FIG. 3 is an opposite side view thereof;

FIG. 4 is a rear perspective view thereof;

FIG. 5 is an opposite side front perspective view thereof; and,

FIG. 6 is an enlarged view of Region 6 identified in FIG. 2. The racetrack shaped areas formed by broken lines and the unshaded areas therein represent eyelets that form no part of the claimed design. The broken lines depicting the remainder of the shoe form no part of the claimed design.

The evenly spaced broken lines in FIGS. 2 and 6 illustrating the enlarged view are for annotation purposes only and form no part of the claimed design.
